CURVED FOLDABLE CLOSURE

Ernest R. Watkins, Anderson, Ind., assignor, by
mesne assignments, to New Castle Products,
Inc., New Castle, Ind., a corporation

Application July 19, 1946, Serial No. 684,891

3 Claims. (Cl. 160—84)

1

This invention relates to a foldable closure for door and partition use.

The chief object of this invention is to provide a closure which is capable of the aforesaid use and which furthermore can be arranged in arcuate form, as distinguished from coplanar form.

The chief feature of the present invention resides in the simplicity of construction, to-wit, the small number of parts, and these so arranged and associated together that the closure, when extended, has in general a curved outline in plan.

Other objects and features of the invention will be set forth more fully hereinafter.

The full nature of the invention will be understood from the accompanying drawings and the following description and claims.

In the drawings

Fig. 1 is a top plan view of the top of a closure in extended and curved relation with intermediate parts broken away and an intermediate section shown in plan, the overhead track being omitted.

Fig. 2 is a side elevational view of the structure shown in Fig. 1.

Fig. 3 is an elevational view of a portion of an intermediate hinge structure or assembly in disassembled relation.

In Fig. 2 of the drawing, 10 indicates a curved track and in general this track is substantially tubular with a central lower slot coextensive therewith.

Rollable on this track is a forward trolley structure indicated generally by the numeral 11 and having spaced wheels 12 and suitably connected as at 13 to a lead post 14. Also rollable on said track is an intermediate trolley structure having a pair of spaced wheels 15 and a connecting portion 16 that is slideable in the slot aforesaid, this connecting member being suitably connected to a so-called central pivot of the closure. There may be as many intermediate trolley structures as desired or required.

The rear post 17 includes an upwardly directed T-shaped member 18, the neck 19 of which extends through the slot of the curved track 10.

For purposes of illustration, the upper portion of a closure, the lower portion thereof and the extreme ends thereof as well as one intermediate portion is illustrated, and more particularly in Fig. 2.

Between the upper and lower hinge series, designated generally by the letters A and B, there may be included any additional series.

Between the lead post connected sections of series A and B and between the rear post con-

2

nected sections of the series A and B there may be provided any suitable number of hinged plate structures, etc., as may be desired or required so that when the closure is extended into closing position, the opening to be closed thereby or the area to be walled off is so closed off.

The foregoing invention is peculiarly applicable to so-called circular or semi-circular bars wherein it is required that the room in which meals are served be separated from the bar proper at such intervals or periods during which it is illegal to dispense intoxicating liquors, the purpose of the closure being to wall off the bar, as stated, and thus leave the remaining area of the room available for restaurant or dancing purposes, and particularly where the bar is of the type previously mentioned.

Herein the A series of the hinge plates comprises two so-called half-length end plates 20 and 21. These have, adjacent the lead post, an angularly disposed portion 20a and 21a, and the adjacent edges are provided with aligned curled portions 22 spaced from each other by means of the notches 23.

25 The other half plate is provided with corresponding curled portions and correspondingly positioned notches so that the curled portions 22 of both half hinge plates may be interfitted with respective notches of the other plate and a common pivot member 24 carried by the bracket 25 pivotally connects the adjacent ends of these half hinge plates together.

The opposite end of each half hinge plate 20 and 21 is provided with curled tongue portions 26 and adjacent notched portions 27. A full length hinge plate 28, such as shown in the lower part of Fig. 3, is connected at one end to the other end of the half-hinge plate 21 by means of the pivot member 29.

30 A half-hinge plate 30, see the upper left hand portion of Fig. 3 and also the upper left hand portion of Fig. 2, is pivotally connected by the pivot member 31 to the half-hinge end plate 20.

Associated with the half-hinge plate 30 and the full hinge plate 28 is another half-hinge plate 32. The two are pivotally associated together and with the full hinge plate 28 by the central pivot or pivot structure 33.

It will be observed that the central portion of 35 the hinge plate 28 includes a biased portion 28a and that the opposite ends terminate in alternate notches and curled tongue portions 34a and 34b, respectively. Notches 34a are at diagonally opposite corners and tongues 34b are at the opposite diagonally opposite corners.

With respect to the plate 30, it also is provided with alternate notches 35 and curled tongue portions 36. Similarly plate 32 is provided with alternate notches 37 and tongue portions 38, and the remote ends thereof, see Fig. 3, include tongues at diagonally opposite corners of the pivotally connected half hinges 30 and 32 and notches at the other diagonally opposite corners.

Herein hinge plate 28 includes a longitudinally directed central notch 39 of considerable length and leading from one edge thereof in the central portion 28a. A pair of slits 40, see the lower half of Fig. 3, form an upper strip 41, a lower strip 42 and an intermediate strip 43.

Strips 41 and 42 are similarly directed, that is, partially bowed, and strip 43 is similarly but oppositely bowed to form a bearing for the pintle 33.

Hinge plate 30 includes the notch 44, the curled tongue 45 and the elongated notch 46 in the offset or biased end portion 30a. The half hinge plate 32 also includes in its offset or biased portion 32a a pair of curled tongues 47, a notch 48 and an elongated notch 49.

It will be observed that the notches and tongues are of progressive offset character and interfit so that the two half-hinge plates can be pivotally connected together by means of the pintle 33 and provide an elongated notch 46-49 to accommodate the pintle supporting portions 41, 42 and 43 of the full hinge plate 28, the notch 39 thereof accommodating the aforesaid sequentially arranged tongues 45 and 47 of the half hinge plates.

The pintle member 33 is what might be termed a central pintle member. A similar full hinge plate 28 is connected at one end to the more remote end of the previously mentioned hinge plate 28, and a half hinge plate 30 is connected to the remote end of the half hinge plate 32, such connections being effected by the pivotal members 50 and 51, respectively.

Any one of the central pivot members 33 may carry the intermediate trolley 15-16 aforesaid. The rear lead post 17 is similarly connected to half hinge plates 52 and 53 as at 54, and the remote ends of said half hinge plates are connected to a full hinge plate 28 and a half hinge plate, such as 32.

It will be obvious from the foregoing therefor that each series comprises a sequentially connected number of full hinge plates, and connected to the intermediate portion of each hinge plate is a half hinge plate, and the same are connected together as illustrated in Fig. 3, and that the series A aforesaid terminates in half hinge plates 20 and 21 at one end and 52 and 53 at the opposite end.

By reason of this construction it will be noted that in extension and collapse the closure conforms generally to the curvature of the track 10, this being permitted by the inclusion of half hinge plates as a sequential series, and that these half hinge plates as a sequential series cross, as it were, the sequential series of full hinge plates, the hinges having a common depth or height, same being permitted by reason of the slots or notches 46, 49 and 39.

With reference to series B it will be observed that the central pivots 33 need not extend from one series to the other although if desired they may do so. Preferably, however, each of the lateral pivots, such as indicated at 29, 31, 50 and 51, are coextensive with the height of the closure so that the covering material omitted here-

from and not illustrated herein, but which is suitably attached thereto by means of fixtures associated with the aperture 60, for example, will conform to and fold, as determined by the closure, in its movement from extended to closed position, and vice versa.

The lower series B is substantially identical to the upper series A in that the full length hinges are in vertical registration and the several half length hinges are in vertical registration. However, as shown in Fig. 2, the tongue and notch arrangements may be reversed, that is, as if the structure were inverted and turned it would be identical.

Otherwise, the construction of the lower series conforms to that of the upper series and any intermediate series may conform to either series A or B, previously described.

It would appear that the primary function of the full length hinge is to insure uniformity of extension and contraction in the closure so that the folds will be uniformly formed and maintained, which otherwise would not be the case if all of the hinge units were of half length character.

It will be obvious, of course, that if all of the intermediate hinging were of full length hinges and of intersecting character, the foldable closure would not assume a curvilinear extension or contraction but, of necessity, would be confined to coplanar movement, and the utilization of intermediate hinges of intersecting character and of full length is specifically disclaimed herefrom for that reason.

The degree of extension can be limited by the cooperation of the half hinge portions at one or both ends of the closure, as set forth broadly in copending application Serial No. 554,873, filed September 20, 1944.

While the curvature of the track 10, as represented by the curvature of the foldable closure in extended relation, see Fig. 1, is of appreciable magnitude, it is to be understood that foldable closures have been applied to curved tracks where the radius of curvature has been of three feet or greater. Where the radius of curvature is below three feet other difficulties are encountered.

It furthermore is to be observed that for certain types of closures, such as those associated and used in lieu of a communion rail structure, but a single crossed series of the aforesaid hinge arrangement would be required since the height of such closure or curtain would not be very great.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. An extensible and collapsible closure structure movable arcuately comprising in combination two sequentially connected series of hinge plate elements, the two series crossing each other at regular intervals, one series including half length elements at the ends and a plurality of full length elements therebetween and the other series comprising substantially all half length elements, the series where crossing having common pivotal connection.

2. A structure as defined by claim 1 wherein the two series are of the same width and where crossing have staggered transversely disposed notches, the structure having the same width as a series and the two series being interfitted one with the other at the staggered notches.

3. In a foldable and extensible closure for association with a curved track the combination of a lead post, a lead post connected trolley engageable with the track and guided thereby, at least one additional trolley engageable with the track and guided thereby, and hinge plate structure means including two sequentially connected series of hinge plate elements, the series crossing each other at regular intervals, one series including a pair of half length elements at the ends and a plurality of full length elements therebetween, the other series comprising substantially all half length elements, the two series where

crossing having a common pivotal axis, and pin-tle means coincident with one of said common axes and operatively connected to the second mentioned trolley, the two series being of the same width and where crossing have staggered transversely disposed notches, the structure means having the same width as a series and the two series being interfitted one with the other at the staggered notches.
